UNITED STATES PATENT OFFICE.

JOSEPH L. WRIGHT, OF WASHINGTON, DISTRICT OF COLUMBIA, ASSIGNOR, BY MESNE ASSIGNMENTS, TO JAMES R. GARFIELD, TRUSTEE, OF CLEVELAND, OHIO.

TELEPHONE-EXCHANGE SYSTEM.

1,244,571.

Specification of Letters Patent. Patented Oct. 30, 1917.

Application filed February 26, 1912. Serial No. 680,015.

To all whom it may concern:

Be it known that I, JOSEPH L. WRIGHT, a citizen of the United States, and resident of Washington, District of Columbia, have 5 invented certain new and useful Improvements in Telephone-Exchange Systems, of which the following is a specification.

My invention relates to telephone exchange systems, and especially to semi-automatic systems which employ switching mechanism controlled by operators for effecting connections between subscribers.

The general object of this invention is the improvement of the systems mentioned.

15 Some of the improvements may be stated as follows:

To simplify the operator's impulse or sending device, so that the impulses instead of passing through the various cam springs 20 and contacts of the key-board are sent directly through the operator's circuit to the automatic switches.

To regulate the impulses from the sending device when transmitted to the driving magnets of the various switches, and to remove the static charge from the impulse conductors:

25 To insure positive release between the various automatic switches:

30 To insure full strokes of the operating magnets when the various switches are testing for idle contacts:

35 To provide for selective party line ringing from either side of the line to ground or full metallic:

To produce trunk connections from a manual switching center to a semi-automatic exchange with double supervision and control by the manual operator:

40 To provide special switching means which can be common to more than one operator for originating calls and supervising connections; and

45 To form the various primary trunks into groups and to provide each group with an independent controlling means for picking out idle key-sets.

To dispense with the operator's transmitter so that it will not be necessary for 50 her to ask the number of the wanted party, as this function is controlled automatically by a phonograph attachment or other suitable means.

My invention is illustrated in the accompanying drawings, wherein:

Fig. 1 shows a subscriber's line equipment and control circuit.

Fig. 2 shows a primary and first selector circuit.

Fig. 3 shows a second selector circuit.

Fig. 4 shows a connector circuit equipped for party line selective ringing.

Fig. 5 shows a subscriber's line equipment, and also the arrangement for indicating changed numbers.

Fig. 6 shows the key-set control circuit, together with a time element controlling device or kick-off switch.

Fig. 7 shows the circuit of the operator's key-set switch and its associated shifting switch.

Fig. 8 shows an operator's keyboard and sending device.

Figs. 8^a and 8^b show the circuits whereby the operator's transmitter is replaced by either a phonograph or suitable tone test signal.

Fig. 1^a shows a portion of an operator's cord circuit and trunk terminating in a manual exchange.

Fig. 2^a shows a trunk from the manual exchange terminating in the semi-automatic exchange in a first selector switch.

Fig. 6^a shows the circuit used for control for distributing the trunks from the manual exchange to operator's key-set switches.

Fig. 2^b shows the circuits and method of controlling reverting calls.

Fig. 9 shows the arrangement of the various figures for a call from the subscriber in the semi-automatic exchange to another subscriber in the same exchange.

Fig. 10 shows the arrangement of the various figures where a call is from a subscriber in a manual exchange to a subscriber in the semi-automatic exchange.

Fig. 11 shows the arrangement of the figures for a reverting call.

Referring to Fig. 1, the subscriber's station at A is equipped with apparatus usual in common battery exchanges and the line wires from this station terminate at the central office in a line relay 2. The line relays are divided into groups, there being ten groups to each one hundred lines. Each group of ten line relays is common to one

group relay 3. The group relay when actuated makes the row contact in the primary switch busy, while the line relay when actuated makes the individual contact in the primary selector switch busy.

The switch W starts to rotate whenever the group relay is energized, and continues to rotate until an idle primary switch is picked out.

10 Referring now to Fig. 2, the primary switch C is shown, which picks out the calling line. This switch first starts to rotate until the row wiper 64 picks out the busy row contact and after reaching this contact 15 it ceases to rotate and steps vertically until the individual busy test contact, leading to the line relay 2, is found.

The first selector switch is shown at D, and responds to impulses from the sending 20 device to pick out an idle trunk leading to a second selector switch in the proper row.

The wipers 63 of the primary switch C and wipers 56 of the first selector switch D are joined, as indicated by the heavy lines, 25 for conversational purposes. The tip and sleeve conductors are separated by the condensers 43 and 44. Through relay 23 and the retardation coil 26 talking current is furnished to the calling subscriber. Relay 30 21 is the starting relay of the primary switch, and corresponds to the line relay 2 (Fig. 1), as it controls the action of the operator's key-set switch (Fig. 7). Relay 22 is the row test relay, while 24 is the individual 35 test relay. Relay 25 is operated when the key-set switch picks out the trunk, and remains energized while the impulses are being transmitted, thereby opening the trunk conductors. Relay 27 is the test relay of the 40 first selector switch, and remains energized while the test wipers 57 are passing over busy contacts. Relay 28 is energized whenever either the rotary or vertical magnets of the primary switch are operated and also 45 when the vertical magnet of the first selector switch is operated. The circuits of these magnets are normally completed through the back contacts of this relay 28, and so, therefore, when it is actuated, the magnet circuits 50 are opened. The action thus set up between the relay and the magnets causes the latter to vibrate and to continue to do so until their energizing circuits are opened.

The resistance coil 42 is placed in series 55 with the rotary relay 29. This relay receives impulses from the operator's sending device and operates magnet 34, causing the switch D to rotate. When the magnet 34 operates, it closes its associated contact 60 springs and places ground between the coil and the winding of the relay 29. This action of the magnet 34 serves to regulate the action of the repeating relay 29 and the magnet 34. This arrangement does away 65 with the necessity for fine adjustment be-

tween the repeating relay and the magnet which it operates and also serves to take up any irregularity of the impulses transmitted by the operator's sending device.

In case the conductors leading to the repeating relays have any static charge, it is 70 dissipated by the ground being placed between the coil and the relay at the end of every impulse received from the sending device.

75 Referring now to Fig. 3, the second selector switch at E is operated first in a rotary direction, to pick out the row and then in a vertical direction, to pick out the idle contact in the row, and is similar to 80 the first selector switch shown at D. 81 is the repeating relay, and is in series with the regulating coil 86. 82 is the interrupter relay corresponding to relay 28 (Fig. 2). 83 is the test relay used in picking out an 85 idle connector switch.

Referring now to Fig. 4, the connector switch G is provided with a set of wipers 390, leading to talking conductors of the called line, and also with wipers 391 leading to the cut-off relay 108 (Fig. 5). 305 and 310 are the repeating relays and 90 respond to impulses from the operator's sending device. 315 is a control relay and removes the relay 325 and retardation coil 335 95 from the wipers, while the switch G is passing over busy contacts. 320 is the tip battery supply relay, and responds when the called subscriber answers. 340 is the ringing relay, operated by the commutator 370. 100 This relay is cut off by the action of the relay 330 controlled by relay 320 when the called subscriber answers. 345 is the busy test relay, and upon acting when a busy line is found, locks itself through the test wire 105 306. This relay connects a suitable busy tone test, which is connected to the wire 341, to the trunk conductor 301, signaling the calling subscriber when the called for line 110 is busy. The action of this relay also operates the release magnet 365, restoring the switch G. A controlling or party line distributing switch is shown at F. The contacts and wiper of the portion J cut on the generators 356, 357, 358 or 359 to either the tip or sleeve contact of the ringing relay 340. The contacts and wiper of the portion I serve to restore the distributing switch 115 to its normal or idle position. The contacts and wiper of the portion H serve to connect 120 ground to either the tip or sleeve contacts of the ringing relay 340. When the portion J cuts on generator to the tip contact, the portion H cuts on ground to the sleeve contact, and when the portion J cuts on generator to the sleeve contact, the portion H cuts on ground to the tip contact. With this 125 arrangement, it is possible to ring subscriber's bells connected to either tip or sleeve side of the line to ground, as well as to ring 130

them over a metallic circuit. Portion H of the switch also serves to release the connector switch G after the called subscriber hangs up his receiver, or when the calling subscriber hangs up in case the called subscriber does not answer.

When the switch F is in its normal position, the wiper of H rests on the contact 334, the wiper of I on the contact 336, while the wiper of J rests upon the contact 338.

A suitable tone test is connected to the wire 392, and is connected to the contact of the ringing relay 340 through the condenser 370 and retardation coil 665, so that whenever this relay operates, the calling subscriber is aware that the called subscriber is being rung.

The two repeating relays 305 and 310 each have windings common to the resistive coil 370. In this connector circuit, the impulses are regulated by both the rotary and vertical magnets 350 and 355 respectively, and also by the action of the magnet 360, controlling the switch F.

Fig. 5 shows a subscriber's station at AA connected to the regular line equipment. Connected to this line is a polarized relay 120. This relay is connected to the line through the terminals 116 and 117, and also connected to the jack 110, which is located before a special or information operator. This jack has an associated lamp 109, which is lighted by the armature 114 engaging the contacts 115. This polarized relay is tuned or responds to the same current as the subscriber's bell formerly located at A².

The regular operator receiving a call for this line, not knowing that the telephone has been removed, puts the call through in the regular manner, thereby causing the generator current to be placed on the called line, which would ordinarily have operated the subscriber's bell at A². Instead of, however, operating this bell, the relay 120 is operated, causing the lamp 109 to light. The special operator thereupon places the plug into the jack 110, and connects her telephone-set across the conductors 105 and 106. This action energizes the tip relay in the connector circuit (Fig. 4) preventing any further action of the ringing relay. The special operator informs the calling subscriber that the number of the party he has called for has been changed, and gives him the new number. The jack 110 is provided with designating strips in which are placed both the old and the new number of the party whose telephone has been changed. The calling subscriber thereupon hangs up his receiver, calls again, and gives the regular operator the new number.

The special operator, withdrawing the plug from the jack 110, releases the connector in the same manner as would a called subscriber.

Referring now to Fig. 6, the switch shown at Y corresponds to the switch W (Fig. 1) and picks out an idle operator's key-set switch.

The switch X is the time element control switch and comes into action when the relay 130 and the relay 132 have been held energized beyond the maximum time limit. The relay 132 is energized as soon as an idle key-set switch is picked out, and should only remain energized long enough for the key-set switch (Fig. 7) to pick out the tenth contact in the tenth row. The magnet 77 causes the switch X to rotate when the contact springs 36 are closed by a suitable cam on the sending device. These contacts are closed once at each rotation.

We will assume that the relays 132 and 130 have been held energized beyond the maximum time and the switch X is rotating. When the wiper x reaches one of the contacts connected to the wire 139, the circuit of relay 78 is closed to ground through the contacts of relay 132. The switch X continues to step at each rotation of the sending device, and when the wiper x reaches one of the contacts to which the relay 76 is connected, this relay operates and performs the following functions: Ground is placed on the wire 149 through the wiper and contacts of the lower bank of the switch W (Fig. 1) to wire 60 operating relay 29, thereby causing the switch D to take one step. Ground is also placed on wire 144, 142 to the release magnet 166 of the switch M, thereby restoring it. The wires 18 and 148 are also opened, thereby disconnecting relay 5 and relay 21. The falling back of this latter relay, disconnects relay 130 (Fig. 6) unlocking relay 78, and no further action takes place.

If a calling subscriber is connected to the primary switch C, and a faulty connection takes place, as just described, he can hang up his receiver and as the switch D has taken one step, the circuit of the release magnet 132 is closed and the switch C will restore, after which the switch D drops back. After hanging up, the subscriber can make a recall, and become connected to another trunk.

The switch X performs no functions with regular connections, unless the key-set switch and trunk should become tied up, whereupon it comes into play and releases the tied-up apparatus.

Referring now to Figs. 7 and 8, the key-set switch and operator's key-board and sending device are shown. The switch M carries the wipers 167, 168 and 169, and in fact, this switch operates in the same manner as the switch C (Fig. 2). The wipers 167 connect to the tip and sleeve sides of the trunk shown in Fig. 2, over which the operator converses with the calling sub-

scriber, and over which the impulses are transmitted. 168 is the row wiper and picks out the group of ten, in which the calling trunk is located. Relay 154 is connected to 5 the individual test wiper which picks out the particular trunk in the group calling. Relay 156 is the signal relay, and pulls up in series with relay 25 (Fig. 2) when the trunk is picked out, and when energized 10 closes the circuits of the two lamps 243 and 244, (Fig. 8), notifying the operator of a call. Relay 152 is the starting relay and corresponds to relay 21 (Fig. 2), while 153 is the row test relay. Relay 155 15 responds when the operator presses the answering button 248, thereby connecting her telephone set across the tip and sleeve conductors of the trunk. 157 is actuated when the operator presses the starting button 20 ton 247. The action of this relay disconnects relay 155, and connects the starting wire controlled by the cam 231 to the stepping magnet 161, thereby causing the switch arms to step over the banks N, O, P. This 25 stepping magnet is operated once at each rotation of the sending device and cuts on the impulses from the keyboard in regular order. The order in which these impulses are transmitted, is as follows: At the first 30 rotation of the sending device, impulses corresponding to the thousands are sent over the tip side of the trunk. At the second rotation, a single test impulse is sent over the sleeve side of the trunk. At the third rotation, impulses corresponding to the hundreds are sent over the tip side of the trunk, and at the fourth rotation, a single test impulse is sent over the sleeve side of the trunk. At the fifth rotation, the selective 35 impulses are sent over the tip side of the trunk, and at the sixth rotation the hundreds impulses are sent over the sleeve side of the trunk. At the seventh rotation, the tens impulses are sent over the tip side 40 of the trunk, and at the eighth rotation, the single test impulse is sent over the sleeve side of the trunk.

At the next rotation of the sending device, the wiper passing over the bank of 50 contacts P, closes the circuit of the relay 158, causing the switch to rapidly rotate until it reaches its normal position. Just before reaching its normal position, however, the circuit of the release magnet 166, 55 of the key-set switch M is energized, thereby restoring it to its normal position and preventing the operator listening in or interfering with the connection.

Relay 163 corresponds to relay 28 (Fig. 60 2), and causes the magnets 164, 165 and 161 to vibrate until their energizing circuits are opened. The operator's keyboard, shown in Fig. 8, consists of five rows of buttons, each row having ten buttons. Number 1

button of each row is connected to a contact 65 operated by the cam 232. Number 2 button of each row is connected to a contact operated by the cam 233. Corresponding buttons in each row are connected to the same contact. The contact controlled by the cam 70 232 is closed just long enough to keep the relay 160 (Fig. 7) energized, while one impulse is being transmitted by the commutator 242. If number 10 button is down, relay 160 would be closed by the cam 241 just 75 long enough for ten impulses to be transmitted by the commutator 242. The contacts of the commutator 242 are connected directly to a normally opened contact of relay 160, and when this relay is energized, 80 the impulses are connected to either the tip or sleeve side of the trunk, depending upon the position of the arm in regard to the contacts of the bank N. The buttons or keys shown in these five rows, in Fig. 8, are of 85 the usual locking and indicating type. When any one button of a certain row is depressed, it will release the button formerly depressed. The buttons 246, 247 and 248 are of the non-locking type, and the contacts 90 controlled by them are only closed while the operator is pressing the button.

Referring now to Fig. 1^a, the operator's cord circuit terminates in a plug P^a. The answering end of the cord circuit is not 95 shown, but the talking conductors are separated by condensers in the usual manner. The sleeve relay 415 is energized in series with relay 425 when the plug is placed in the jack J^a. The action of the relay 415 100 lights the lamp 411. The relay 410 is the tip supervisory relay and is actuated when the called party answers.

The portion of the trunk shown terminates at the manual exchange in the jack 105 J¹, through the contacts of relay 430. The jack J¹ has associated with it a signal lamp 414, and a button 416. The lamp lights when the operator at the semi-automatic exchange answers. When the operator at the 110 manual exchange presses the button 416, the relay 430 is operated, severing the trunk circuit and connecting her telephone set across the out-going end, thus preventing the calling subscriber from hearing her repeat the number to the operator at the semi-automatic exchange. 115

Referring now to Fig. 2^a, the trunk conductors 412, and 413 from the manual exchange are connected for conversational purposes to the wipers 447 of the first selector switch through the windings of a repeating coil 419 and condensers 421. The wipers 448 act as test wipers and also form a part of the release circuit. Relay 460 is 120 normally connected across the answering end of the trunk conductors in series with the coil 495. The relay 460 is very sensitive, 125

and will respond when the trunk plug P^1 is inserted in the jack J^1 . The coil 495 , however, is of such a high resistance that the relay 410 (Fig. 1^a) will not pull up or even hold up through it. Relay 445 is actuated when the key-set switch picks out the trunk and in turn closes the circuit of relay 440 . This latter relay disconnects relay 435 , which is the starting relay and 10 responds to relay 21 (Fig. 2). Relay 470 is the rotary repeating relay, while 455 is the test relay of the first selector switch. Relay 450 is of a high resistance, and is actuated when the called subscriber answers. 15 The action of this relay shunts out the resistance coil 495 , thereby actuating relay 410 (Fig. 1^a), notifying the operator at the manual exchange that the subscriber at the semi-automatic exchange has answered his 20 telephone.

Referring now to Fig. 6^a, the circuit shown is similar to that of Fig. 6. In fact, the main difference is that the time element switch, instead of releasing the various 25 switches after a predetermined time, simply removes ground from the winding of relay 130 . All of the connections of the switch Y remain the same. When the relay 76 , belonging to the time element switch, is 30 operated, the relay 130 is disconnected. This controlling circuit provides against tying up the trunks from the manual exchange in case several operators plug into trunk jacks at the same instant, thereby 35 holding the relay 130 energized by parallel paths, as the wire 79 is multipled to a group of trunks. In case such a condition should arise, the control switch acts after a suitable time, operating relay 76 , thereby unlocking 40 relay 130 , thus preventing any tie-up.

Referring now to Fig. 2^b, the special first selector switch shown as DD is the same as that at D (Fig. 2). The relay 740 is the test relay, while 750 is the rotary repeating relay. Relay 735 responds when the operator's key-set switch (Fig. 7) picks out the trunk. The keys or buttons 726 , 727 and 741 are placed before the operator and associated with a key-set switch such as shown 50 in Fig. 7.

By pressing button 726 , ground is connected to wire 140 , thereby energizing relay 152 of Fig. 7, causing the switch M to rotate until the last or tenth row contact is found. 55 This tenth contact is connected permanently to ground, and therefore, the switch after reaching this contact will step up vertically until the tenth contact in the row is found. This last or tenth contact is connected per- 60 manently to battery B . Therefore, the switch M will come to rest when this contact is picked out. Other contacts belonging to this set lead to wires 59 , 60 , 61 and 62 of the special reverting call switch (Fig. 2^b).

The operator is now in possession of a 65 special first selector switch and can call any subscriber in the exchange. Relay 730 acts when the called party answers, and lights the lamps 724 . One of the lamps is individual to each operator, that is, where the 70 same special switch is common to a group of operators. In case the switch was individual to a special operator such as the chief or information operator, only one lamp 724 would be needed. When the called party 75 answers, the operator, pressing button 741 connects her telephone-set across the trunk wires, allowing her to converse with the called party. To release the switch or switches, the operator presses button 727 , 80 thereby connecting an impulse from the cam 728 to relay 725 . The action of this relay places a momentary battery impulse to the release magnet 270 and also to the test wiper 748 , thereby releasing both the first selector 85 and second selector switches.

Other features in connection with the various figures will be brought out in the detailed description of operation.

In describing the operation of my system, 90 I will first trace a connection from a calling subscriber in the semi-automatic exchange to another subscriber in the same exchange, using Figs. 1, 2, 3, 4, 5, 6, 7 and 8, and arranged as shown in Fig. 9. 95

The subscriber at A , upon removing his receiver, closes the circuit of the line relay 2 in series with the group relay 3 . This latter relay operating closes the circuit of relay 4 , which in turn connects ground to one 100 terminal of the relay 5 , and also closes the circuit of the stepping magnet 7 . The stepping magnet 7 operating closes the circuit of relay 6 , which in turn opens the circuit of the magnet, causing it to vibrate and step 105 around the wipers of the switch W . This switch will continue to rotate until an idle primary switch, such as shown at C (Fig. 2), is found. As soon as such an idle switch is found, relay 5 is placed in series with relay 110 21 (Fig. 2), by the following path: ground, contact of relay 4 , 5 , 18 , contacts of relay 76 (Fig. 6), 148 , upper bank of switch W , 14 , 21 , 70 , contact of relay 24 to battery B . The relay 5 becoming energized opens the circuit of the stepping magnet 7 , bringing the switch W to rest. Relay 21 operating closes the circuit of the rotary stepping magnet 31 by the following path: battery B , 80 , back contact of relay 24 , 71 , contact of relay 28 , 22 , 31 to ground. The operation of magnet 31 causes the primary switch C to rotate until the wiper 64 reaches the busy contact, to which is connected wire 13 , leading to the contacts of relay 3 . 125

The wiper 64 is carried on the same spindle with wipers 63 and 65 , and while the switch is rotating, the wiper 64 passes over

6 contacts rendered busy by the action of relay 3. As there are ten of these group relays to each one hundred lines, it follows that the wiper 64, to reach its extreme position, passes over ten contacts.

There are ten sets of individual contacts arranged in vertical rows, associated with each row contact, and which the wipers 63 and 65 respectively engage. It therefore follows that after the switch picks out the group in which a line is calling, it will afterward step vertically until the wipers engage the contacts of the calling line.

As soon as the row contact is found, the circuit of relay 22 is closed as follows: battery B, 80, contacts of relay 24, 71, 22, 64, 13, contact of relay 3 to ground. The relay 22 operating disconnects the rotary magnet 31, and in its place connects the vertical magnet 30, thereby causing the switch to step vertically until the busy individual test contact is found. As soon as such a contact is found, the circuit of relay 24 is closed by the following path: battery B, 24, 68, 67, 11, contacts of relay 2 to ground through the contacts of relay 1. The relay 24 operating opens the wire 71, disconnecting relay 22, which in falling back disconnects relay 24 from wire 67 and connects it instead to wire 66. The relay 24 is now placed in series with relay 1 and the operating of this latter relay disconnects line relay 2 and the group relay 3. The operating of relay 24 connects battery to the windings of relays 23 and 25, and the falling back of relay 22 connects ground to the retardation coil 26, and battery is thereby supplied to the calling subscriber for talking purposes.

The relay 21 remains energized until the primary switch finds the calling line, and until the key-set switch finds the calling trunk. The relay 21 when first actuated places battery on the wire 79 to relay 130 to ground, and also places battery to wire 62 leading to the individual test contact of the key-set switch (Fig. 7).

The relay 130 operating closes the circuits of the stepping magnet of the switch Y through the normally closed contacts of relays 131 and 132. The switch magnet 133 in operating closes the circuit of the interrupter relay 134, which causes a vibrating effect between the magnet and the relay, and the switch will continue to rotate until an idle key-set switch is found. When such a switch is found, as shown in Fig. 7, relay 131 is placed in series with relay 132 (Fig. 7) by the following path: ground, contacts of relay 130, 131, 138, through the bank contacts of Y, 140, 152, 195, 196, 197, to battery through the operator's jack 400.

Relay 131 operating places battery on wire 136 to relay 132, causing it to operate. As soon as this latter relay operates, it places

ground on wire 130, thereby shunting relay 131. This direct ground makes the wire 140, which is multiplied to other Y switches, busy. The operating of relay 132 also places ground on the row wiper of the key-set switch by the following path: ground, 139, bank contacts of Y, 141, to the row contact (Fig. 7). Relay 152 operating places ground on the rotary magnet 165, through the back contact of relay 153, thereby causing the switch M to rotate. This switch will continue to rotate until the row contact is found, whereupon the circuit of the relay 153 is closed by the following path: battery B, contacts of relay 152, 176, 153, 171, 168, 141, 139, contacts of relay 132 to ground.

The action of the key-set switch M is identical with that of the primary selector switch C (Fig. 2).

The operating of relay 153 disconnects the rotary magnet 165 and in its place connects the vertical magnet 164, thereby causing the key-set switch to step vertically until the busy individual test contact is found. As soon as this contact is found, the circuit of the relay 154 is closed as follows: ground, 154, 172, 62, 80, contacts of relay 21 to battery B. The operating of relay 154 disconnects relay 152, thereby cutting off the vertical magnet causing the key-set switch M to rest on contacts leading to the calling primary trunk (Fig. 2). Relay 152 becoming disconnected opens the circuit of relay 153, and this latter relay in falling back places relays 156 and 25 in series by the following path: ground, back contact of relay 153, 175, back contact of relay 157, 202, contacts of relay 155, 156, 193, contacts of relay 158, 170, 169, 59, 25 to battery B through the contacts of relay 24. The operating of relay 25 disconnects relay 21 and relay 5 (Fig. 1). The releasing of relay 5 frees the switch W, allowing it to pick out other primary switches.

Relay 156 operating places battery on wires 181 and 183, thereby lighting the two lamps 243 and 244 (Fig. 8).

As soon as relay 21, in Fig. 2, became disconnected, battery was removed from the individual test contact of the key-set switch, thereby allowing the relay 154 to fall back. The action of relay 21 also opens the circuit of relay 130, which in turn opens the circuit of relay 132, and allows the switch Y to be used by other trunks in picking out key-set switches.

In the present system, I have provided ten primary switches such as shown in Fig. 2, for each one hundred lines. Each group of ten primary switches, as shown in Fig. 2, is provided with one Y switch for picking out idle key-set switches.

The wire 141, leading from the Y switch to the row contact of the key-set switch, is

not multiplied. As soon as the Y switch picks out a key-set switch, ground is placed on the row contact of the selected switch only, thus preventing interference in case 5 other Y switches, associated with other trunks, are picking out key-set switches at the same time. In no case is ground placed on more than one row contact of any key-set switch at the same instant. This method 10 allows calls to come in from different groups of trunks at the same time, and yet prevents interference.

In Fig. 1, the switch W is individual to one hundred lines and picks out a group of 15 primary switches, and in this case the row contacts of a group of primary switches are multiplied, and only one primary switch at a time of a particular group acts at the same instant.

20 The percentage and grouping of the primary switches can be increased or decreased to suit traffic conditions.

The lighting of the two lamps 243 and 244 notifies the operator of a call, and she 25 then presses the button 248, operating relay 155, thereby connecting her telephone-set across the tip and sleeve conductors of the trunk. The action of relay 155 disconnects relay 156, extinguishing lamps 243 and 244, 30 but at the same time lighting the lamp 245. Relay 156 becoming disconnected allows relay 25 (Fig. 2) to fall back, closing the tip and sleeve conductors of the primary trunk and allowing the operator to converse 35 with the calling subscriber.

Each operator is provided, preferably, with three key-sets, enabling her to handle calls without loss of time, for while one call is going through on one key-set, she can receive calls on the other two.

The cams of the sending device, shown at 40 230 to 241 inclusive, may be common to a group of key-sets. The commutator 242, however, is preferably individual to one key-set or to one operator.

In the present instance, I have shown the exchange to be of ten thousand lines capacity, and in case of a larger exchange, it would be necessary to add additional 45 selector switches and additional rows of buttons to the operator's keyboard.

The operator, after getting the proper number from the calling subscriber, presses one button in each row corresponding to the 50 number desired, and then presses the starting button 247, which closes the circuit of relay 157 by the following path: ground, 247, 186, 157, 193, 170, 169, 59, 25, to battery B through the contacts of relay 24. The relay 55 25 again operating opens the trunk conductors to prevent the calling subscriber from hearing the impulses.

The operating of relay 157 disconnects the relay 155, extinguishing lamp 245 and

causing the guard lamp 244 to light. The 60 action of this relay also connects the starting wire 189 connected to the contacts operated by the cam 231 to the stepping magnet 161. As soon as the cam contact springs are operated, the wipers of the shifting 70 switch at N, O, P take one step and connect the impulse wire 191 to the tip side of the trunk 150 through the contacts of relay 160.

If number 9 button in the row R is 75 pressed, the relay 160 will be held energized by the operation of the cam 240 until nine impulses have been transmitted by the commutator 242. These impulses operate the rotary relay 29 (Fig. 2) by the following path: ground, 242, 191, 190, 192, contacts of relay 160, N, 150, 167, 60, 54, 29, 42, cam springs 40 to battery B. The relay 29 responding to these impulses, closes the circuit of the rotary magnet 34, causing the first selector switch D to rotate and come 80 opposite a group of trunks in the ninth row. As soon as the springs operated by the rotary magnet 34 are closed, ground is at once placed between the winding of relay 29 and the coil 42, thereby shunting out 85 relay 29, and relay 29 falling back removes battery from the winding of the magnet 34 itself. It will be noticed that if the impulse from the sending device has been a trifle long, the relay 29 would be shunted out just as soon as the magnet 34 finishes its stroke.

After these rotary impulses have been sent, the starting cam 231 causes the shifting switch to take another step, thereby connecting wire 198 to the sleeve side of the trunk 151. The relay 160 is now held up by the action of the cam 230 until a single impulse is transmitted. This impulse operates the relay 27 (Fig. 2) by the following path: 100 ground, 242, 191, 190, 192, contacts of relay 160, 198, N, 151, 167, 61, relay 27, cam springs 40 to battery B.

The relay 27 receiving this impulse, is held energized by the following path: battery B, contacts of relay 25, locking contacts of relay 27, 58, contacts of relay 28, 72, 32, cam springs 41 to ground. These cam springs were operated when the switch D took its first rotary motion. The operating 110 of relay 27 closes the circuit of the vertical magnet 33, by the following path: battery B, contacts of relay 28, 71, contacts of relay 27, 33 to ground. The magnet 33 in operating closes the circuit of the relay 28, 115 which in turn opens the circuit of the magnet 33 itself. The action of this relay and magnet causes the latter to vibrate, stepping the switch D vertically. When the circuit of relay 28 is closed by the action of the magnet 33, the circuit of relay 27 is itself 120 partially opened, but it will remain energized by the test wiper 57 in passing over

- grounded or busy contacts, for while the magnet 28 is operated and the wiper 57 comes to rest on an idle contact, the relay 27 will at once become deenergized and disconnect the vertical magnet 33.
- 5 The controlling of the test relay 27 in the foregoing manner, insures a full step of the magnet 33, as the wiper 57 fully engages the test contacts before the relay 27 is opened by the action of relay 28.
- 10 As soon as the switch D takes its first vertical step, or while it is in the act of taking this step, the cam springs 40 are opened, thereby disconnecting relay 27 and 15 29 respectively from the tip and sleeve sides of the trunk. After the test wiper 57 picks out an idle trunk, the subscriber is connected to an idle second selector, as shown in Fig. 3.
- 20 At the third rotation of the sending device, impulses corresponding to the hundreds are sent over the tip side of the trunk to the second selector switch (Fig. 3), operating relay 81. This relay is connected to 25 the tip side of the trunk 90, through the cam springs 88. The action of relay 81 closes the circuit of magnet 85, causing the switch E to rotate and come opposite a row of contacts leading to connector switches.
- 30 At the fourth rotation of the sending device, a single test impulse is sent over the sleeve side of the trunk, operating relay 83. This relay 83 closes the circuit of the vertical magnet 84, causing the switch to step 35 vertically until the test wiper 102 comes to rest on contacts leading to an idle connector switch. The test relay 83 is controlled in the same manner as the test relay 27 (Fig. 2), and the rotary relay and rotary magnet 40 are controlled and regulated in the same manner as the rotary magnet and rotary relay in Fig. 2. At the first vertical step of the switch E, the cam springs 88 are opened, thereby disconnecting relays 81 and 83 respectively from the tip and sleeve sides of 45 the trunk.
- The calling subscriber is now connected to contacts of an idle connector switch.
- At the fifth rotation of the sending device, impulses corresponding to the button 50 depressed in the row V (Fig. 8) are sent over the tip side of the trunk operating relay 310 of the connector (Fig. 4). The action of this relay closes the circuit of the 55 stepping magnet 360 of the party line distributing switch by the following path: ground, 321, contacts of relay 330, 323, 360, 318, contacts of relay 320 to battery B. The switch F takes a number of steps corresponding to the impulses controlled by the button in the row V (Fig. 8). In the present instance, I have shown the generator 60 356 connected to the first two contacts in the bank J, so that if either one or two impulses are transmitted, this generator will be connected to the sleeve side of the trunk 304. If six or seven impulses are transmitted, the same generator will be connected to the tip side of the trunk 302. The contacts are arranged in this manner because one of the party line frequencies is also used for straight or independent line ringing. We will assume that five impulses have been transmitted. Therefore generator 359 will become connected through the 75 fifth contact of the bank J to the sleeve contact in the ringing relay 340, while ground is connected from the bank H to the tip contact of the ringing relay 340.
- The action of relay 310 also closes the 80 circuit of the relay 315, by the following path: battery B, 319, 315, contacts of relay 305, 306, 102 (Fig. 3), 89, contacts of relay 82 to ground.
- At the sixth rotation of the sending device, impulses corresponding to the button pressed in the row T are sent over the sleeve side of the trunk, operating relay 305. This relay operating, unlocks relay 315, and closes the circuit of the rotary magnet 355 90 by the following path: battery B, contacts of relay 305, 314, cam springs 380, 316, 355 to ground. This magnet operating causes the connector switch G to rotate and come opposite a group of contacts in which the 95 desired line is located. The action of relay 305 also closes the circuit of relay 330. The action of this relay disconnects the stepping magnet 360 of the switch F, and in its place connects the vertical magnet 350.
- At the seventh rotation of the sending device, impulses are sent over the tip side of the line operating relay 310 a second time. This relay responding, now operates the 100 vertical magnet 350, causing the switch G to step vertically and bring the wipers into engagement with contacts leading to the desired line. The action of relay 310 again energizes relay 315, preventing annoying clicks while the wipers are passing over 105 busy contacts.
- When the switch G takes its first vertical step, the cam springs 380 operate and disconnect the rotary magnet 355.
- At the eighth rotation of the sending device, a single test impulse is sent over the sleeve side of the trunk, operating relay 305 a second time. This relay now operating, connects the test relay 345 directly to test wiper 391. If the called line is busy, this 115 relay 345 will become energized and lock itself from battery to one terminal, to ground, through the other terminal, to the test wire 306. The action of this relay places ground on the release magnet 365, and causes the 120 switch G to restore, and also connects a busy tone from the wire 341 to the trunk 301, notifying the calling subscriber that the line is busy.
- In case the called for line is not busy, 130

the relay 345 will not be affected. Relay 305 acting again unlocks 315, and falling back places the relay 325 in series with the cut-off relay 108 (Fig. 5) by the following path: battery B, contacts of relay 315, 313, 312, 325, 311, 308, 391, 107, 108 to ground. The action of relay 108 disconnects the line relay. The action of relay 325 closes the sleeve side of the trunk, as indicated by the heavy lines, and disconnects the repeating relay 310. Relay 325 places battery to the winding of the tip relay 320, and also closes the circuit of the ringing relay 340 by the following path: ground, commutator 370, 340, 326, contacts of relay 325, 324, contacts of relays 330 and 315, 322, vertical magnet 350 to battery. The action of this ringing relay connects the generator 359 to the sleeve conductor 304 and ground, to the tip conductor 302, thus ringing the subscriber's bell AA at intervals. At each actuation of the relay 340, a suitable tone test is sent over the sleeve side of the trunk through the condenser 370 and coil 665, notifying the calling subscriber that the called for party is being rung.

At the next rotation of the sending device, the relay 158 (Fig. 7) is connected to battery through the bank P. The action of this relay places ground on the magnet 161, and also unlocks relay 157. The magnet 161 vibrates rapidly and causes the shifting switch to rotate until the wipers reach their normal or resting position. Just before reaching the normal position, the wiper of the portion P places the relay 158 in series with the release magnet 166, thereby causing the switch M to restore. This switch restoring disconnects the operator's key-set from the primary trunk, and it is immediately available for other calls.

When the calling subscriber removed his receiver during the non-ringing interval, he energized the relay 320. The action of this relay unlocks 330 and disconnects relay 305, closing the tip side of the trunk as indicated by the heavy lines. The falling back of relay 330 disconnects the ringing relay 340.

The calling and called subscribers are now able to converse without interference, and the talking circuit throughout the various figures is indicated by the heavy lines.

When the called subscriber hangs up his receiver, the relay 320 falls back and the circuit of the magnet 360 is closed by the following path: ground, commutator 353, I, 398, contacts of relay 330, contacts of relay 315, 321, contacts of relay 330, 323, 360, 318 to battery B through the contacts of relay 320. This magnet 360 will continue to vibrate until the wiper of the portion I rests on the contact 336. Just before the wiper at I reaches this contact, the wiper at H

closes the circuit of the release magnet 365 by the following path: battery B, 365, 332, H, 327 to ground through the contacts of relay 315. The action of magnet 365 restores the switch G to its normal position.

The calling subscriber, upon hanging up his receiver, causes the relay 23 (Fig. 2) to fall back, thereby closing the circuit of the release magnet 32 by the following path: battery B, cam springs 38, 73, contacts of relay 23, 58, 72, 32, 75, cam springs 41 to ground. Magnet 32 operating releases the primary switch C, and in restoring, it opens the cam springs 38, thereby removing the shunt from magnet 35 and allowing it to become energized as follows: battery B, 35, 73, contacts of relay 23, 58, 72, 32, 75, cam springs 41 to ground. Operating the magnet 35 causes the first selector switch D to restore, opening the cam springs 41, thereby opening the circuit of magnet 35.

As soon as the tip relay 23 falls back, and while the switch C is restoring, battery is connected to the winding of magnet 93, energizing it as follows: battery B, cam springs 38, 73, contacts of relay 23, 58, 57, 96, 93, 100, cam springs 87 to ground. The action of magnet 93 restores the switch E to its normal position.

In case the called for party does not answer, then the calling subscriber also releases the connector switch. This release is brought about as follows: When the second selector switch (Fig. 3) restores, ground is removed from the test wire 306, thereby unlocking relay 330, just as though the relay 320 were energized. The relay 330 falling back in this manner closes the circuit of the magnet 360 by the same path as formerly traced, thereby restoring all parts of the connector switch to its normal or idle position.

I will now trace a connection from a calling subscriber in the manual exchange to a subscriber located in the semi-automatic exchange. The circuits used in this connection are 1^a, 2^a, 3, 4, 5, 6^a, 7 and 8, arranged in the manner shown in Fig. 10.

The operator at the manual exchange, upon receiving a call for someone at the semi-automatic exchange, places calling plug P¹ into an idle trunk jack, J¹. The insertion of the plug energizes the relay 415 in series with the coil 425. The action of relay 415 lights the lamp 411, and connects the tip relay 410 to the tip side of the cord circuit.

Battery being placed on the trunk wires 412 and 413 by the relays 410 and 415, energizes relay 460 (Fig. 2^a). The energizing of this relay closes the circuit of relay 435 by the following path: ground, contacts of relay 460, 434, cam springs 441, 432, contacts of relay 440, 433, 435 to battery B. The action of relay 435 places battery on wire 62, leading to the individual test con-

tact of the key-set switch (Fig. 7), and also places battery on wire 79, energizing relay 130 (Fig. 6^a). The switch Y picks out an idle key-set switch in the same manner as switch Y (Fig. 6), and need not be described again.

When the key-set switch (Fig. 7) picks out the trunk (Fig. 2^a), the relay 445 is placed in series with relay 156 in the same manner that relay 25 (Fig. 2) is placed in series with relay 156. The action of the key-set switch in picking out and becoming connected to the trunk in Fig. 2^a, is identical with that in picking out the trunk in Fig. 2. The action of relay 445 energizes relay 440 by the following path: battery B, contacts of relay 445, 431, 440, 434, to ground through the contacts of relay 460. Relay 440 disconnects relay 435, which in turn opens the circuit of relay 130.

When the operator receives the signals 243, and 244 (Fig. 8), she presses the answering button 248, thereby releasing relays 156, and 445. Relay 445 falling back, closes the circuit of relay 420 (Fig. 1^a) as follows: battery B, 427, contacts of relay 440, 424, cam springs 441, 418, 420, to ground. The action of relay 420 lights the lamp 414, and notifies the operator at the manual exchange that the operator of the semi-automatic exchange has answered the call. She thereupon presses the button 416, energizing relay 430, severing the trunk, and connects her telephone-set to the outgoing end of the trunk, preventing the calling subscriber hearing her converse with the other operator.

The operator of the semi-automatic exchange, upon learning the desired number, sets it up on her keyboard in the regular manner and the action of the sending device and relays of the key-set switch is identical, as already described.

The first set of impulses are sent over the tip side of the trunk, operating the rotary relay 470, which in turn closes the circuit of the rotary magnet 475, causing the switch to rotate and come opposite a row of contacts leading to second selector switches. At the second rotation of the sending device, a single test impulse is sent over the sleeve side of the trunk, operating relay 455. This relay closes the circuit of the vertical magnet 480, and maintains the circuit closed until an idle second selector switch is picked out, whereupon the test relay 455 drops back. At the first step of the switch, the cam springs 441 are opened, thereby releasing relay 420 (Fig. 1^a), which in turn extinguishes lamp 414, notifying the operator that the call has been started. At the first vertical step of the switch, the cam springs 442 are operated, thereby disconnecting relays 455 and 475.

The balance of the impulses go forward 65 and operate the second selector and connector switch as previously described. After the connection is entirely built up, the key-set switch (Fig. 7) restores as before, and the subscriber at the manual exchange is 70 able to converse with the subscriber at the semi-automatic exchange.

The relay 450 is of a very high resistance, and is placed in multiple with the tip relay 320 to the connector, when the latter is 75 operated. This relay 450 responds when the calling subscriber removes his receiver, and short circuits the resistance coil 495, thereby allowing the relay 410 (Fig. 1^a) to become energized, extinguishing lamp 411. 80 This action notifies the operator at the manual exchange that the called party is answering.

When the called subscriber hangs up his receiver, he restores the connector switch in 85 the same manner as previously described.

The restoring of the connector switch allows the relay 450 to fall back, thereby cutting in the resistance 495, and causing the relay 410 (Fig. 1^a) to fall back and 90 light the lamp 411. The operator, upon getting this disconnect signal, withdraws the plug P¹ from the jack J¹, and thereby deenergizes relay 460. This relay falling back, opens the circuit of relay 440, which 95 in turn closes the circuit of the release magnet 485 by the following path: battery, commutator, cam springs 490, 428, contacts of relay 440, 426, 485 to ground. Battery from this commutator is also placed on the wire 100 429 to the test wiper 448, thereby restoring the second selector switch (Fig. 3). The commutator shown connected to the cam springs 490 is preferably a portion of the sending device shown in Fig. 8, and delivers one impulse at each rotation. 105

For reverting calls, the various figures are arranged as shown in Fig. 11.

The operator receiving a call from a party line subscriber who desires to converse with 110 some one on the same line tells him to hang up his receiver and wait for a few seconds. She then presses the starting button (Fig. 8) causing the release of the primary and first selector switches shown in Fig. 2, and 115 also of the key-set switch shown in Fig. 7. In case of small exchanges, the local operator is provided with a set of buttons 726, 727 and 741, as shown in Fig. 2^b, which control the action of the special first selector 120 switch DD.

In larger exchanges, however, a party upon asking for a reverting call, would be transferred or connected at once to the information or special operator, who upon getting his number and the number of the party desired on the same line, tells him to hang up his receiver. In this latter case, 125

- the special operator would be provided with the buttons 726, 727 and 741, but in either case the operation would be the same. When the button 726 is pressed, ground is placed 5 on the wire 140, leading to the relay 152 in Fig. 7. The action of this relay closes the circuit of the rotary magnet, causing the switch M to rotate until the last row contact is found, which as before stated, is 10 permanently connected to ground. When this row is reached, the relay 153 operates, disconnecting the rotary magnet and in its place connecting the vertical magnet, causing the switch M to step vertically until 15 the last contact in the row is found. This contact is permanently connected to battery, and its associated contacts lead to the special switch DD. The signal lamps 243 and 244 are lighted in the usual manner, when 20 the key-set switch becomes connected to the special reverting call switch. The operator sets up the number of the wanted line, and the impulses from the sending device are sent in the regular order.
- 25 The first set of impulses being sent over the tip side of the trunk operate the rotary relay 750, which in turn closes the circuit of the rotary magnet 260, causing the switch DD to rotate and bring its wipers 30 opposite a row of contacts leading to second selector switches. At the second rotation of the sending device, a single test impulse is sent over the sleeve side of the trunk, operating test relay 740. This relay closes 35 the circuit of the vertical magnet 265, causing the switch to step vertically and automatically pick out an idle second selector switch. As soon as such a switch is picked out, relay 740 falls back, disconnecting the 40 vertical magnet 265. At the first vertical step of the switch DD, the relays 740 and 750 are disconnected from the tip and sleeve sides of the trunk respectively.
- The balance of the impulses are sent in 45 the same manner as already before described, and operate the second selector and connector switches, the latter switch picking out the desired line.
- The relay 730 holds up in multiple, and 50 responds with the tip relay of the connector when the called subscriber answers. The action of this relay lights the lamp or lamps 724, notifying the operator that the subscriber has answered. By pressing button 741, she is enabled to listen in on the 55 connection and find out whether the two parties on the same line are conversing. Upon finding the connection all right, she presses button 727 which sends an impulse 60 to the relay 725, and this relay in turn places battery to the release magnet 270, and also to the release magnet of the second selector switch, thereby causing the two switches to restore. This leaves the calling
- and called subscriber on the same line in 65 possession of the same connector switch, and when both parties hang up, the switch is restored to its normal condition.
- As soon as the operator receives the signals 243 and 244, she releases the button 726, 70 and when the connection is entirely established, the key-set switch restores in the usual manner and can be used for incoming calls.
- Referring now to Fig. 8^a, means are 75 shown whereby the operator simply pressing the listening button connects a phonograph in place of her ordinary transmitter.
- The operation of this circuit is as follows: The operator presses the listening button 848, closing the circuit of the regular listening relay 155, the action of which connects the receiver and the secondary winding of the induction coil to the tip and sleeve conductors of the trunk. The circuit 85 of the relay 800 is also closed by the following path: ground, contacts of 848, 804, 800, contacts of 840 to battery B. The relay 800 operating closes the circuit of relay 805 through the contact springs 845. 90
- The three disks 810, 820 and 830 are mounted on the same shaft, and as shown, are constantly rotating in the direction indicated by the arrows. The projection 825 on the disk 820 is a little in advance of the 95 projection 815 on the disk 810. When the projection 825 opens the contacts 845, the circuit of relay 805 is momentarily opened, but as soon as the contacts 845 are again closed the relay 805 has its circuit again 100 completed through the contacts of relay 800 and contacts 845. When the projection 815 opens the contacts 840, the circuit of relay 800 is broken, and it immediately falls back and remains in that condition as the button 105 848 is of a non-locking type. The relay 805 being energized and the relay 800 being de-energized connects the transmitting device 855 to the winding of the primary of the operator's induction coil. 110
- The disk 830 has mounted upon it a phonographic record which will reproduce certain words such as "Number please." The word "Number" begins at the point 831 on the line 835, over which a needle travels. 115 This point is located immediately following the break of the contacts 840, caused by the action of the projection 815.
- It, therefore, follows that as soon as the relay 800 falls back, the words "Number 120 please" are reproduced by the phonographic horn 850, which in turn transmits the sound to the transmitting device 855. As soon as the complete sentence has been sent a suitable number of times, the relay 805 is broken 125 by the contacts 845 being opened by the projection 825. The relay 800 being de-energized, the relay 805 has no guarding or

additional energizing circuit. The falling back of relay 805 disconnects the wire 801, preventing any further action of the transmitting device through the operator's induction coil.

5 In case the operator wishes to have the number repeated, she simply has to press the button 848 again, which will connect the phonographic attachment to the primary 10 induction coil as before.

10 The relay 155 remains energized until the starting button is depressed, as previously described.

15 Referring now to Fig. 8^b, a similar arrangement is shown, but instead of providing a phonographic attachment, I have simply shown a suitable tone test arrangement at 880. This tone test is provided with a constantly operating commutator 870, which 20 makes and breaks the circuit of the primary of the transformer 875. The secondary of the transformer in turn has its circuit interrupted by a suitable make and break device 880, which produces a musical tone when 25 connected to the primary of the operator's induction coil.

When the operator presses the answering or listening button 848, the regular listening relay 155 pulls up, connecting the operator's telephone-set across the tip and 30 sleeve conductors of the trunk. The button 848 is of a non-locking type, and while in the depressed position, the tone test is connected to the primary of the induction coil, and 35 from there through the secondary to the calling line. The calling subscriber hearing this tone test, at once gives the number he desires and the operator, after pressing the starting button, releases the relay 155, as 40 already described. With this arrangement, it is not necessary to connect the tone test at a predetermined point, as was necessary with the method shown in Fig. 8^a.

45 With either of the foregoing arrangements, the duties of the operator are simplified, and the efficiency of the service increased, as the operator cannot converse with the calling subscriber. The subscribers in turn, knowing that they cannot converse 50 with the operators, will give their numbers promptly upon getting the proper signal, thereby reducing all delays. It will also be noticed with either arrangement, as shown, that when the calling subscriber is giving 55 his number, the primary of the operator's induction coil is opened, thus preventing her hearing the noises in the operating room, which ordinarily are taken up by the transmitter, and she can, therefore, hear the calling 60 subscriber more distinctly.

Having thus described my invention, what I claim and desire to secure by Letters Patent is:

1. In a telephone system, the combination 85 with a switching mechanism, of a magnet

for operating the mechanism, a relay associated with and for operating said magnet, a resistance connected with the winding of the relay, means for energizing said relay and means controlled by said magnet for 70 short circuiting the winding of said relay.

2. In a telephone system, the combination with a switching mechanism, of a magnet for operating said mechanism, a relay associated with and for operating said magnet, 75 a resistance connected in series with the winding of the relay, means for energizing the relay to operate said magnet, and means operable by said magnet to short circuit the winding of the relay.

80 3. In a telephone system, the combination with a switching mechanism, of a magnet for operating said mechanism, a relay associated with said magnet, a resistance connected in series with the winding of the relay, means for intermittently energizing the relay to operate said magnet, and means operable by the magnet to intermittently short circuit the winding of the relay.

85 4. In a telephone system, the combination with a step-by-step switching mechanism, of a relay, a resistance, a source of current, an impulse device, said resistance, source of current and impulse device being connected in series with the winding of said relay, a 90 magnet for operating said mechanism and having a winding in circuit with a source of current, means responsive to the operation of said impulse device and relay for interrupting the circuit of the magnet winding 100 to operate said step-by-step mechanism and means responsive to the operation of the magnet for short circuiting the relay.

95 5. In a telephone system, the combination with a switching mechanism, of a magnet 105 for operating said mechanism and having a winding in circuit with a source of current, a relay associated with the magnet, a resistance and a source of current in series with the winding of said relay, an impulse device 110 in series with the winding of said relay to intermittently operate said relay to make and break the circuit through the magnet, thereby operating said switching mechanism, and means operated by the magnet for connecting ground to the relay circuit between 115 the relay winding and resistance to short circuit said relay winding.

120 6. In a telephone system, the combination with a switching mechanism, of means for actuating said mechanism, means for interrupting the actuating means, a relay, an impulse device for operating said relay and means for connecting the winding of said relay to an element of said switching mechanism and interrupting means.

125 7. In a telephone system, the combination with a switching mechanism, of means for actuating said mechanism, means for interrupting the actuating means, a relay, means 130

- for energizing the relay, and means responsive to the operation of said relay for temporarily connecting the winding of the relay to an element of said switching mechanism, and interrupting means.
- 5 8. In a telephone system, the combination with a switching mechanism, of means for actuating said mechanism, a relay, a device for energizing the relay, means responsive to the action of the relay for connecting energy to said actuating means, a second relay, means for connecting the winding of said second relay in circuit with a source of current, means responding to the operation of said second relay for controlling said actuating means, and means on the switching mechanism for controlling said first relay.
- 10 9. In a telephone system, the combination with a switching mechanism, of a magnet for actuating the mechanism, a relay, means for energizing the relay, means responding to the action of said relay for energizing the magnet, a second relay, means responsive to said second relay for breaking the magnet energizing circuit, and means dependent on the action of said magnet for making and breaking the circuit of the second relay.
- 15 10. In a telephone system, the combination with a switching mechanism, of a magnet for actuating the mechanism, a relay, means for energizing the relay, means responding to the action of said relay for energizing the magnet, a second relay, means responsive to said second relay for breaking the magnet energizing circuit, means dependent on the action of said magnet for making and breaking the circuit of the second relay, and means on the switching mechanism adapted to be connected to the winding of said first relay to keep said relay in circuit until an idle contact on said switch is reached.
- 20 11. In a telephone system, the combination with a switching mechanism, of a magnet for actuating the mechanism, a relay, an impulse device for operating said relay, means responding to the action of said relay for connecting the magnet winding in circuit with a source of current, a second relay, means responsive to the second relay for interrupting said magnet energizing circuit, means responsive to the action of said magnet for making and breaking the circuit of said second relay, a contact maker on the switching mechanism and means responsive to the operation of said impulse device for connecting the winding of the first-named relay to the contact maker.
- 25 12. In a telephone system, in combination with means for producing impulses in recurring cycles, of a step-by-step switch actuated one step for each cycle, and adapted to be connected to said impulse-producing means, means for determining the number of im-
- pulses to be transmitted and means responsive to the action of said impulse number determining means for controlling the connection of said impulse-producing means to said step-by-step switch.
- 30 13. In a telephone system, in combination with a plurality of line circuits, of switching mechanism for interconnecting the lines comprising selector and connector switches; means for producing impulses, a step-by-step switch adapted to be connected to said impulse-producing means, means for determining the number of impulses to be transmitted comprising a relay, a key-set having a group of keys corresponding to the number necessary to control the selector and connector switches, circuits including said relay winding controlled by said keys, and means for energizing said relay to connect the impulse-producing means to the step-by-step switch for a sufficient period to transmit a number of impulses to the selector and connector switches as determined by a key operated.
- 35 14. In a telephone system, in combination, a plurality of line circuits, switching mechanism for interconnecting the lines, means for actuating said switching mechanism comprising means for producing groups of impulses in recurring cycles, a step-by-step switch actuated one step for each cycle and adapted to change the connection of said impulse-producing means to the switching mechanism for interconnecting the lines, means for determining the number of impulses to be transmitted and means for controlling the connection of said impulse-producing means to said step-by-step switch.
- 40 15. In a telephone system, in combination, a plurality of lines, automatic switching mechanism for interconnecting the lines, means for actuating said switching mechanism, means for controlling said actuating means comprising means for producing impulses in recurring cycles, a step-by-step switch actuated one step for each cycle, and adapted to change the connections of said impulse-producing means to the automatic switches to transmit impulses thereto in predetermined order and number through a succession of cycles, a relay for controlling the connection of the impulse-producing means to the step-by-step switch, a key-set comprising a number of groups of keys corresponding to the number of groups of impulses necessary to control the switching mechanism and adapted to control the operation of the relay, means for effecting the successive connection of key-controlled circuits to the relay and means for determining the period of the operation of the relay.
- 45 16. In a telephone system, the combination with line circuits including a line serving a plurality of subscribers' stations, of automatic switches for interconnecting the

- lines, including selector and connector switches, party-line selective ringing apparatus associated with the connector switches and adapted to be set therethrough, an operator's circuit and switching means for interconnecting the same to any one of a plurality of selector switches, means associated with the operator's circuit for actuating said selector switches when so connected, and
- 5 means for making a reverting call over the party-line serving a plurality of subscribers' stations comprising a special selector switch associated with said operator's switching means, means for rendering the special
- 10 switch active in response to a reverting call, connector trunk terminals in said special switch and means for restoring the operator's switching means and the special switch after a reverting call connection has
- 15 been established, leaving only the connector switch associated with the calling-called line.
17. In a telephone system, the combination with line circuits including a party-line, of a switching device, an operator's circuit
- 20 adapted to be connected with said switching device and party-line, means for making a reverting call over the party-line comprising special switching means connected to the switching device, means for rendering the
- 25 special switching means active in response to a reverting call, means for connecting said special switching means to the party-line and means for restoring the switching device and special switching means to
- 30 normal position after the reverting call connection has been established.
18. In a telephone system, the combination with line circuits including a party-line, of means for interconnecting the lines, an
- 35 operator's circuit, switching means for connecting the operator's circuit to said line circuits and party-line, means for making a reverting call over the party-line comprising special switching means connected to
- 40 said switching means, means for rendering the special switching means active in response to a reverting call, means for enabling the operator to call any subscriber in the exchange to enable the operation of
- 45 the interconnecting means and means for restoring the switching means and special switching means after the reverting call connection has been established.
19. In a telephone system, the combination with line circuits including a party-line, of a key-set comprising a number of groups of keys, a switching device associated with said key-set, an operator's circuit adapted to be connected with said switching device
- 55 and party-line, means for making reverting calls over the party-line comprising special switching means connected to the switching device, means for rendering the special switching means active in response to a
- 60 reverting call, means for connecting said special switching means to the party-line, means for actuating said connecting means for the special switch comprising an impulse-producing device controlled by keys in the key-set, and means for restoring the special switch and switching device to normal position after the reverting call connection has been established.
20. In a telephone system, the combination with line circuits including a party-line, of a switching device, an operator's circuit adapted to be connected with the party-line and switching device, means for restoring the switching device and connections to normal condition when a reverting call is to be made, means for making a reverting call comprising special switching means permanently connected to the switching device, means for rendering the special switching means active in response to a reverting call, means for temporarily connecting said special switching means to the party-line, means for actuating said temporary connecting means, and means for restoring the special switch and switching device to normal position after the reverting call has been established.
21. In a telephone system, the combination with line circuits including a party-line, of automatic switching mechanism including a connector switch for interconnecting the lines, an operator's circuit, switching means for connecting the operator's circuit to any one of a plurality of elements in said automatic switching mechanism, means for making reverting calls over the party line comprising special switching means connected to the switching means for the operator's circuit, means for rendering the special switching means active in response to a reverting call to enable the operation of the automatic switching mechanism and means for restoring the switching means for the operator's circuit, the special switching means and part of the automatic switching mechanism after the reverting call connection has been established, leaving only the connector switch associated with the calling-called line.
22. In a telephone system, the combination with line circuits including a party-line, of automatic switching mechanism including selector and connector switches for interconnecting the lines, party-line selective ringing apparatus adapted to be operated through the automatic switching mechanism, an operator's circuit, impulse-producing means and a key-set comprising a number of groups of keys, a switching device associated with said key-set and impulse-producing means for connecting the operator's circuit to the automatic switching mechanism, means for making reverting calls over the party-line

- comprising special switching means common to a group of key-set switching devices and permanently connected to a contact on each of the operators' key-set switching devices, 5 means for rendering the special switching means active in response to a reverting call to enable the transmission of impulses for operating the automatic switching mechanism, and means for restoring the key-set 10 switching device, the special switching means and selector switches when the connection has been established, leaving only the selector switch associated with the calling-called line.
- 15 23. In a telephone system, the combination with line circuits including a party-line, of automatic switching mechanism including selector and connector switches for interconnecting the lines, an operator's circuit and switching device adapted to be connected to the party-line by the switching mechanism, means for restoring the switching mechanism and device to normal condition when a reverting call is to be made, 20 means for making a reverting call comprising special switching means permanently connected to the switching device, means for rendering the special switching means active in response to a reverting call, means 25 for temporarily connecting said special switching means to the automatic switching mechanism, means for actuating the automatic switching mechanism, means for ringing the wanted party on the party-line, a 30 supervisory signal operative when the connection is established, and means for restoring the special switch, operator's switching device and selector switches of the automatic switching mechanism to normal position 35 after the reverting call connection has been established, leaving only the connector switch associated with the calling-called line.
24. In a telephone system, in combination, a manual switchboard and an operator's circuit associated therewith, automatic switching mechanism, a plurality of line circuits, a portion of the lines being wanted or called lines and connected to contacts in the automatic switching mechanism and another portion 50 of the lines being calling lines and connected to jacks in the manual switchboard, trunking means extending between the manual switchboard and the automatic switching mechanism and terminating in contacts in the latter, a second operator's circuit associated with the switching mechanism, means for connecting the manual operator's circuit to communicate with the second operator without interfering with the calling lines, 55 and means for actuating the switching mechanism to interconnect the lines in response to proper communication from the manual operator.
- 60 25. In a telephone system, in combination a manual switchboard and an operator's circuit associated therewith, automatic switching mechanism, a trunk line extending between said switchboard and mechanism and terminating in contacts in the latter, a plurality of line circuits, a portion of the lines being calling lines and connected to jacks in the said switchboard, another portion of the lines being wanted or called lines and connected to the switching mechanism, a second operator's circuit associated with the automatic switching mechanism, means for temporarily severing the trunk line and connecting the manual operator's circuit to the outgoing end to permit the manual operator to communicate with the second operator, 75 means for actuating said automatic switching mechanism to connect the trunk line to a wanted line in response to a communication to the second operator, means for signaling the wanted subscriber and a supervisory signal actuated when the subscriber on said called or wanted line responds.
26. In a telephone system, in combination, a manual switchboard and an operator's circuit associated therewith, an automatic switching mechanism and a second operator's circuit associated with said mechanism, subscribers' lines connected to jacks in the switchboard, other subscribers' lines connected to contacts in the automatic switching mechanism, trunking means extending between the switchboard and automatic switching mechanism, means for connecting the manual operator's circuit to the trunking means and establishing connection with the second operator's circuit to enable the manual operator to communicate with the second operator without interfering with the calling line, means controlled by the second operator for actuating the switching mechanism to interconnect the subscribers' lines in response to a communication from the manual operator, a signal associated with the trunking means and rendered operative when the second operator responds, another signal associated with the trunking means and rendered operative when the called subscriber responds, and means for disconnecting the second operator's circuit when the called subscriber responds.
27. In a telephone system, in combination, a manual switchboard and a plurality of operators' circuits associated therewith, an automatic switching apparatus and a second operator's circuit associated with said apparatus, subscribers' lines terminating in jacks in said manual switchboard, other subscribers' lines connected to contacts in the switching apparatus, a trunking means connecting the switchboard and switching apparatus, 120 means controlled by the second operator for connecting calling subscribers' lines terminating in the manual switchboard with sub-

- scribers' lines connected to the switching apparatus, and means for preventing the tying up of the trunking means when a plurality of operators at the manual switchboard 5 utilize the same trunking means.
28. In a telephone system, in combination, subscribers' lines, switching apparatus for interconnecting the lines, including primary selectors adapted to become automatically connected to calling lines, first selector, second selector and connector switches interconnected, an operator's circuit and means associated with the switching apparatus for actuating the selector and connector switches, 10 means for releasing the several switches and means maintaining the release of the first selector inoperative until the primary switch restores thereby insuring the release of the second selector switch.
29. In a telephone system, in combination, line circuits, link circuits interconnecting the same, primary selector switches for connecting link circuits with calling lines, first selector, second selector and connector switches 15 for connecting the links with wanted lines, an operator's circuit with controlling apparatus associated therewith for actuating the selector and connector switches, a secondary selector switch for connecting the operator's circuit with the links, means for releasing the several switches and means maintaining the release of the first selector inoperative until the primary switch restores thereby insuring the release of the second selector 20 switch.
30. In a telephone system, subscribers lines including one or more party lines having ringers connected from opposite sides to ground, automatic switching mechanism 25 for interconnecting the subscribers' lines including a connector switch, a plurality of sources of ringing current, and selective means associated with a connector switch for connecting said sources of current to either the tip or sleeve side of the line to enable the operation of said ringers from either side of the line to ground or full metallic.
31. In a telephone exchange system, in combination, subscribers' lines, automatic switches for interconnecting said lines, a special selective switch associated with the connective switches and adapted to select a wanted line only on the initiative of an operator, said switch being normally disconnected from the operator's position, means at said position whereby the operator may take control of said switch, and means also at said position for directing the movements of the switch for selective purposes.
32. In a telephone exchange system, in combination, subscribers' lines including one or more party lines, automatic switches including selector and connector switches for 35 interconnecting the same on calls originated by the subscribers, a plurality of operators' positions, means whereby a party line subscriber in calling may become connected to one of said positions, a special selector switch common to said positions adapted when actuated to select a wanted line only without becoming connected with a calling line, means at each operator's position for receiving incoming call signals, means at 40 each position for obtaining control of said selector switch, and means at each position for actuating said switch in a predetermined manner to select and ring a wanted line, whereby a party line subscriber may call an operator, and if he desires connection with another party on his own line, the operator may thereupon initiate connection with said line through the special selector switch, the initial calling means being released.
33. In a telephone exchange system, in combination, subscribers' lines including one or more party lines, automatic switches including selector and connector switches for 45 interconnecting the same on calls originated by the subscribers, a plurality of operators' positions, means whereby a party line subscriber in calling may become connected to one of said positions, a special selector switch common to said positions adapted when actuated to select a wanted line only without becoming connected with a calling line, means at each operator's position for receiving incoming call signals, means at 50 each position to determine the busy or idle condition of said special selector switch, means at each position to take possession of said selector switch if idle, means at each position for determining the actuation of said switch to select a connector and to actuate the same so as to effect connection with a wanted line and to project ringing current over the same, and means to release and restore said special selector switch when 55 a connector has been thus connected with a line, whereby a party line subscriber may call an operator, and a connector switch may thus be attached to his line so as to enable him to converse with another party thereon, while the special selector switch is released and rendered available for other similar calls at any operator's position.
34. In a telephone exchange system, in combination, subscribers' lines and automatic switches for interconnecting the same, including primary selectors adapted to become automatically connected to calling lines, first selectors individually connected to the several primary selectors, and subsidiary switch groups accessible only through the first selectors, means for actuating each of said switches, means for maintaining the same in actuated position, and electromagnetic means for releasing the 60 65

- same, together with a release circuit for said magnetic means of each switch, said release circuit being so arranged and connected that when a primary selector is off-normal, and its associated first selector is off-normal with its wipers resting on contacts connected to a subsidiary switch, the release circuit of the primary selector and said subsidiary switch will be connected through contacts closed in the first selector switch, and the release circuit of said first selector switch will be open, including off-normal contacts in the primary selector, whereby closure of the primary release will also simultaneously close the release circuit of the subsidiary switch, and the release of the first selector will not be closed until the primary switch is completely restored, an operative interval being then produced during which the primary and subsidiary release circuits are not severed.
35. In a telephone exchange system, in combination, subscribers' lines including one or more party lines having ringers connected from opposite sides to ground, automatic switches for interconnecting the subscribers' lines including connector switches, and ringing means for a connector circuit comprising the following instrumentalities: a selective switch associated with the connector switch and containing a plurality of generator contacts, a plurality of line contacts and a plurality of ground contacts, said generator contacts being duplicated and the line and ground associated therewith in opposite pairs, whereby the connection of a generator to one side of the line will be accompanied by the connection of ground to the other side.
36. In a telephone exchange system, in combination, subscribers' lines including one or more party lines having ringers connected from opposite sides to ground, automatic switches for interconnecting the subscribers' lines including connector switches, and ringing means for a connector circuit comprising the following instrumentalities: a ringing selector switch, a plurality of sources of ringing current of distinctive characteristics connected to duplicate contacts in said switch, a ringing relay in the connector having line and generator contacts in opposite pairs, and line and ground connections in the ringing selector connected to said ringing relay contacts in opposite pairs, whereby when the ringing selector is set, a selected generator will thereby be connected to one side of line and ground to the other, when the ringing relay is energized.
37. In a telephone exchange system, in combination, subscribers' lines and automatic switches for interconnecting the same in one office, other subscribers' lines and a manual switchboard interconnecting the same at another office, and trunking means connecting the two offices comprising the following instrumentalities: a trunk circuit extending between the offices and terminating on a jack in the manual switchboard and a selector switch in the automatic office, a signal associated with said jack, and a controlling circuit for said signal extending from the manual to the automatic end of the trunk and adapted to be controlled in the operation of said selector switch, means at the automatic office whereby the trunk switch may be controlled by an operator, automatic means for connecting said operator's circuit with the trunk in response to an incoming call, and automatic means for disconnecting the same when the desired call is completed to the wanted line.
38. In a telephone exchange system, the combination with a switching mechanism, of a magnet for operating said mechanism, a relay associated with said magnet, a resistance connected in series with the winding of the relay, means for energizing said relay to operate said magnet, and means controlled by said magnet to connect ground between the winding of said magnet and resistance to cause the deenergization of said relay.
39. In a telephone exchange system, the combination with a switching mechanism, of a magnet for operating said mechanism, a relay, a resistance connected in series with the winding of the relay, means for energizing the relay to operate said magnet, and means operable by said magnet to connect ground between the winding of said relay and said resistance to dissipate any static charge on the conductors connected with said relay winding.
40. In a telephone system, the combination with a switching mechanism, of a magnet for operating said mechanism, a relay having resistance in series with its winding, means for intermittently energizing the relay to operate said magnet, and means operable by the magnet to intermittently short circuit the relay by connecting ground between the winding of the relay and said resistance.
41. In a telephone system, an automatic switch provided with a test wiper, of a magnet for actuating said switch, a relay, means for energizing the relay, means controlled by said relay for controlling the operation of said magnet, a second relay, means controlled by said second relay for disabling said magnet, means controlled by said magnet for operating the second relay to cause the deenergization of the first relay, and means controlled by the operation of the first said relay to cause its winding to be connected to the test wiper of said switch.
42. In a telephone system, the combination with an automatic switch, of a magnet for operating said switch, a relay for oper-

ating said magnet, a second relay, means for initially energizing the first said relay, and means controlled thereafter by said switch and the second relay for maintaining the 5 first said relay energized.

43. In a telephone system, the combination with an automatic switch provided with a test wiper, a magnet for operating said switch, a relay for operating said magnet, 10 a second relay operated by said magnet, means for initially energizing said first relay, and means controlled thereafter by said test wiper and the second relay for maintaining the said first relay energized.

44. In a telephone system, the combination with a manual switchboard and an operator's circuit associated therewith, automatic switching apparatus adapted to interconnect with subscribers' lines, a second operator's 20 circuit, means controlled at said manual switchboard for interconnecting both of said operators' circuits, means controlled at the second operator's circuit for causing said automatic switching apparatus to interconnect with said subscribers' lines.

45. In a telephone system, the combination with calling and called subscribers' lines, an operator's position, trunk lines terminating in automatic switching mechanism 30 extending to said position, a second operator's position, means controlled from the first operator's position for extending the connection from calling subscribers' lines to the second operator's position, and means controlled at said second operator's position for controlling the automatic switching mechanism for extending the connection to the called subscribers' lines.

46. In a telephone exchange system, the 40 combination with an operator's position, means associated therewith for interconnecting with calling subscribers' lines, trunk lines extending to said position and terminating in automatic switching mechanism, 45 a second operator's position, means controlled at the first position for extending the connection from calling lines to the first operator's position over said trunks, means controlled at the second operator's position 50 for extending the connections from the calling subscribers' lines to wanted subscribers' lines by means of said automatic switching mechanism.

47. In a telephone system, the combination with subscribers' lines, switching apparatus for interconnecting the lines, said apparatus including primary switches adapted to be automatically connected to calling 55 lines, first selector, second selector and connector switches adapted to extend the connection from the primary selectors to called lines, means for actuating the selector and connector switches, releasing means for said switches, and means for maintaining the re-

lease of the first selector inoperative until the 65 primary switch restores thereby insuring the release of the second selector switch.

48. In a telephone system, the combination with subscribers' lines, automatic switching apparatus for interconnecting the 70 lines including primary selectors, intermediate selectors and connectors, means for operating said switches in the order named, releasing means for said switches, means for preventing the release of the intermediate 75 switch until after the release of the primary switch.

49. In a telephone system, the combination with a link circuit comprising a primary switch and an associated selector 80 switch, actuating means for said switches, releasing means for said switches, means for preventing the release of the selector switch until after the release of the primary switch.

50. In a telephone exchange system, the 85 combination with a link circuit comprising a primary switch and a selector switch, actuating means for said switches, release magnets for each of said switches, means for short-circuiting the release magnet of 90 the selector switch until after the release of the primary switch so as to prevent the release of the selector switch until after restoration of the primary switch.

51. In a telephone system, the combination with subscribers' lines including a plurality of party lines, some of said lines having a plurality of ringers connected from opposite sides to ground, other of said lines having ringers connected in a bridged circuit across both sides of the lines, an automatic switch for interconnecting with any of said lines, ringing means for said switch, and means controlled by said switch for selectively operating any one of said ringers 105 on any of said lines.

52. In a telephone exchange system, a plurality of trunks, automatic switches for extending said trunks to the lines of called subscribers, operator controlled means external to said trunks for connecting them with the lines of calling subscribers, manually actuated means for directly controlling the operation of said switches, and automatic means for connecting said manually 110 actuated means with said trunks.

53. In a telephone exchange system, a plurality of trunks, automatic switches for extending said trunks to the lines of called subscribers, operator controlled means external to said trunks for connecting them with the lines of calling subscribers, manually actuated means for directly controlling the operation of said switches, and a signal controlled by a called subscriber associated with 120 125 said operator controlled means.

54. In a telephone exchange system, a plurality of trunks, automatic switches for ex-

- tending said trunks to the lines of called subscribers, operator controlled means external to said trunks for connecting them with the lines of calling subscribers, manually actuated means for directly controlling the travel of said switches, automatic means for connecting said manually actuated means with said trunks, and automatic means effective following the extension of a 10 trunk into connection with a called line for disconnecting said manually actuated means from said trunk.
55. In a telephone exchange system, answering operators' positions, subscribers' lines terminating in answering jacks at said positions, trunk lines terminating in trunk jacks at said positions, cord pairs for connecting any answering jack with any trunk jack, other operators' positions, mechanism 15 automatically actuated upon the connection of a cord pair with a trunk jack for temporarily extending the talking circuit of said cord pair to one of said other operators' positions, and traveling switches directly controlled from said other operators' positions for completing a connection extending from the talking circuit of said cord pair to the line of a desired subscriber.
56. In a multi-exchange telephone system, a plurality of answering operators' positions at one exchange, subscribers' lines terminating in answering jacks at said positions, cord pairs and trunk jacks at said 20 positions, trunk lines leading from said 30 trunk jacks, traveling switches, subscribers' lines at a distant exchange, other operators' positions, automatic mechanism for extending said trunk lines to said other operators' positions, and means at said other operators' 40 positions for directly controlling said traveling switches to complete a connection extending from said trunk lines to the lines of desired subscribers at said distant exchange.
45. 57. In a multi-exchange telephone system, a plurality of answering operators' positions at one exchange, subscribers' lines terminating in answering jacks at said positions, cord pairs and trunk jacks at said positions, 50 trunk lines leading from said trunk jacks, traveling switches, subscribers' lines at a dis-
- tant exchange, other operators' positions, automatic mechanism for extending said trunk lines to said other operators' positions, means at said other operators' positions 55 for directly controlling said traveling switches to complete connections extending from said trunk lines to the lines of desired subscribers at said distant exchange, and means, automatically effective following the 60 exercise of said directive control, to disconnect said trunk lines from said other operators' positions.
58. In a telephone exchange system, the combination with an operator's position, of 65 a second operator's position, trunk lines extending from the first operator's position, means controlled at said first position for causing the automatic connection of the trunk lines with the second operator's position, and additional means controlled at the second operator's position for causing the automatic disconnection of said trunk lines.
59. In a telephone exchange system, the combination of an operator's position, trunk 75 lines terminating at said position, automatic switching mechanism associated with said trunk lines, a second operator's position, means for causing the temporary association of said trunk lines with the second position, 80 means at the second operator's position for directing the action of the automatic switching mechanism.
60. In a telephone exchange system, the combination with an operator's position, a 85 calling subscriber's line terminating at said operator's position, a called subscriber's line, automatic switching mechanism for interconnecting the lines, a second operator's position, means controlled at the first operator's 90 position for causing the association of the second operator's position with said automatic switching mechanism, means associated with the second operator's position for thereafter directing the action of the automatic switching mechanism.

In testimony whereof I affix my signature in presence of two witnesses.

JOSEPH L. WRIGHT.

Witnesses:

ARTHUR L. BRYANT,
J. A. WATSON.
